(57) **CLAIM**

The ornamental design for a fan motor, as shown and described.

DESCRIPTION

FIG. 1 is a bottom, front and right side perspective view of a fan motor, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged horizontal cross-sectional view thereof; taken along line 8-8 of FIG. 2, with the internal system omitted.

The broken lines in all views are shown for illustrative purposes only and form no part of the claimed design. The long dash short dash line forms the boundary of the claimed design and forms no part of the claimed design.
